UNITED STATES PATENT OFFICE.

ANDREW R. RIDDERSTROM, OF NAHANT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

FOLDING MACHINE AND METHOD.

Original application filed September 1, 1920, Serial No. 407,336. Divided and this application filed August 11, 1922. Serial No. 581,154.

The present invention relates to folding methods and machines, and more particularly to methods of and machines for folding a binding strip around the edge of a boot or 5 shoe upper to which it is attached. This application is a division of a copending application, Serial No. 407,336, filed September 1, 1920.

The binding strip is usually sewed upon a 10 face of the upper along an edge thereof, after which the strip is folded around the said edge and into even contact with the opposite face. In order that the binding strip, after folding, 15 may lie evenly and smoothly against the said opposite face, it is necessary that the strip be first wiped tightly across the edge to which it is secured and then pulled and held tightly during the folding operation and while it is 20 pressed against the said opposite face; and it is necessary also that the strip be folded exactly at the proper points or lines, and not to one side thereof. This is very difficult of 25 achievement even by hand, and no successful mechanical means for operating upon shoe- 30 upper binding strips have heretofore been devised. Binding strips are therefore still folded laboriously, clumsily and unsatisfactorily by hand, the various operations being 35 performed separately at different times, wasting much time and adding greatly to the cost. It is an object of the present invention to 40 provide an improved method of and machine for folding binding strips. With this and other objects in view, the invention consists 45 of the method and the machine a preferred embodiment of which is hereinafter described, illustrated in the accompanying drawings and defined in the appended claims.

In the drawings, Fig. 1 is a perspective 40 view of portions of the upper, forward part of the machine; Fig. 2 is a section of a shoe upper, showing an unfolded binding strip attached thereto; Fig. 3 is a section similar to Fig. 2 showing the binding strip in finally 45 folded position upon the upper; Fig. 4 is a front view, showing a preferred form of the wiper of the present invention; Fig. 5 is a similar view of the same, illustrating the wiping action of the wiper; and Fig. 6 is a view 50 showing a modified retainer.

The invention is illustrated in the accompanying drawings in connection with the folding of a binding strip 2, of cloth, silk and

the like, around the edge 4 of a sheet of leather or other material 6, such as a boot or 55 shoe upper. An edge 8 of the binding strip is stitched at 12 to a face 10 of the shoe upper along the edge 4, so that the sheet and the strip extend at an angle to each other from the secured-together edges 4 and 8. 60

It will be understood that the invention is equally applicable to other articles than that which is herein chosen for purposes of illustration, and the elements of the article need not necessarily be of the relative dimensions 65 shown.

The shoe upper is initially placed in the machine upon a platform or support 24, with the face 10 of the upper in contact with the support. An end of the free or unsecured edge 26 of the strip 2 is initially moved across and around the secured-together edges 4 and 8, and into the space between a feed point 30 and a plow 32 that stands up integrally from a plate 34. The plate 34 is 70 mounted upon a holder 93 that is secured, as by a set screw 95, to a support 94 that rocks about a rod 96. The machine being set into operation, successive portions of the strip 2 near the stitches 12 are wiped tightly across 75 the secured-together edges 4 and 8, or away from the stitches, as shown more particularly at 36, Fig. 3, by the combined dragging or crowding action against the stock of a wiper 321, Fig. 4, and a retainer 153 or 253, as the 80 stock is fed forward through the machine. In order to enable the wiper 321 to operate, the strip 2 is progressively moved lightly or 85 loosely by the operator's fingers from the position of Fig. 2 more or less into the plane of 90 the shoe-upper sheet 6, as the shoe upper is 95 fed forward through the machine. The successively wiped portions are initially folded around the secured-together edges 4 and 8, 100 by the plow 32 and they are gripped between the feed point and the plow 32. The wiping, and folding and gripping operations are performed upon the successive portions of the strip alternately. The plow-folded portions are then advanced by the feed point 30 and a 105 cooperating feed block 41 to a combined folder and fold presser 42. The feed block 41 is carried integrally with the plow 32 upon the plate 34. The preferred rolling fold presser 42 is described in Letters Patent No. 110 1,527,395, granted February 24, 1925. The

fold presser 42 folds the plow-folded portions of the strip further and presses them down against the other face 16 of the sheet, as shown in Fig. 3. These operations are continued in timed relation to one another until the whole strip has become folded, as described more fully in Letters Patent No. 1,527,396, also granted February 24, 1925. Reference is made to the said Letters Patent for a fuller description of so much of the machine as is not fully disclosed herein, because unnecessary to an understanding of the present invention.

The wiper 321 of the present invention 15 comprises, in its preferred form, a member raised above the platform or support 24 to form a ridge disposed in a position diagonal to the direction of feed. This member is shown secured at 322 to a removable, vertically adjustable bracket 61. As the stock is advanced in the direction of the arrow, Fig. 4, the strip 2 rides over the ridge 321, becoming wiped thereby.

During the left-to-right (as view in Figs. 23 4 and 5) oscillating movement of the rocking support 94, as described in the aforesaid Letters Patent No. 1,527,396, the separated feed point and feed block return from the fold presser toward the wiper to take a new 30 hold upon the stock. The feed elements are thus returned in preparation for the next forward movement of the feed elements. Portions of the strip 2 that have previously been wiped by the wiper 321 are during this return movement engaged by the plow, and by it given an initial fold, as will be clear from Fig. 5.

The retainer 153 disclosed in the said Letters Patent No. 1,527,396 acts to clamp the 40 stock and thus prevent it being pushed outward away from the operating instrumentalities of the machine. The retainer acts also to hold the stock firmly against accidental movement during the return movement of the feed elements. It may, if desired, be caused further to cooperate with the wiper, so as to press down heavily upon the upper directly opposite to the point of action of the wiper, as illustrated in Figs. 1 and 6.

50 A still simpler construction is shown in Fig. 6. Here the retainer 253 acts continuously against the stock, so as to press down upon the stock during the dragging action. The wiper thus cooperates with the retainer to wipe or stretch or crowd the strip tightly 55 away from the stitch line. A spring 254 may be employed to effect this continuous action. The retainer 253 may be pivoted at 256, or otherwise mounted, upon a stationary part 60 of the machine. To minimize possible injurious effects upon the wiper when the stock is removed, the retainer point is, in this construction, preferably made smooth, without teeth. A retainer of this simpler character 55 is particularly adapted for use with a wiper

that is immovable in a direction at an angle to the line of feed. This is because the wiping action of a wiper of this character is entirely due to dragging or crowding the stock over the wiper.

70

The wiping is effected during the forward movement of the feed elements towards the fold presser. The feed elements then return towards the wiper. As the plow is rigid with the feed block, it acts also as a gage. The 75 folding operation of the plow continues until the plow is returned to a point very close to the wiper. Towards the end of the return movement of the feed elements, the feed point descends obliquely to the plow, as described 80 in the said Letters Patent No. 1,527,396, effecting frictional engagement of the strip between the latter and the feed point. The feed point and the feed block then clamp the material in preparation for the next forward 85 feed movement. The feed point and the plow maintain their tight hold upon the strip during the forward movement of the feed elements until the feed point again rises at the end of the said forward movement. As the 90 feed point, the feed block and the plow move forward, they drag the stock over the wiper. It is at this time that the wiping is effected by the raised member 321. The stock is solidly gripped at all times during the forward movement, of the feed elements permitting no opportunity for the stock to slip, and the line of fold of the strip about the edges 4 and 8 is 95 predetermined. The initial, predetermined fold is advanced under the fold presser, by 100 which it is further folded and pressed. The above-described cycle of operations is then 105 repeated.

It has hitherto been proposed, though the proposal has not met with success, to fold 105 by machinery a binding strip about the edge of the upper to which it is sewed after the binding strip has first been wiped across the edge of the upper by hand or in some other manner. It is essential to the successful 110 operation of the illustrative machine that the wiping, folding, etc., be performed in the same machine. Hand wiping is difficult to perform properly. If the wiping is performed by hand before the upper is introduced into the machine, the machine will be 115 unable to correct the errors of hand wiping. This is particularly true when, as is usually the case, cement is employed to cause the strip to stick to the upper after it is folded. The cement causes the strip to stick to the 120 upper in its hand-wiped condition, resisting the action of the machine wiper, so that the latter can not effect the wiping action properly. If the strip is not wiped tightly 125 to start with, it can not, of course, fold properly.

Many parts of the illustrative machine that are not essential to an understanding of the present invention have not been illustrated 130

and described in detail, reference being made for a fuller understanding thereof to the above-mentioned application and Letters Patent.

5 It will be understood that the invention is not restricted to the exact embodiment thereof that is herein illustrated and described. Changes and modifications will therefore obviously occur to persons skilled in the art, and 10 these are considered to be embraced within the spirit and scope of the present invention, as defined in the appended claims.

The invention having been thus illustrated and described, what is claimed as new is:—

15 1. A machine for wiping a strip across the edge of a sheet of material to one face of which, along the said edge, an edge of the strip is secured so that the strip and the sheet extend from the secured-together edges at an 20 angle to each other, the said machine having in combination, a support upon which the sheet is adapted to rest, means for feeding the sheet over the support, and a rigidly secured member raised above the support for 25 wiping the strip across the secured-together edges as the sheet is fed over the support.

2. A machine for wiping a strip across the edge of a sheet of material to one face of which, along the said edge, an edge of the strip is secured so that the strip and the sheet extend from the secured-together edges at an 30 angle to each other, the said machine having, in combination, a support upon which the sheet is adapted to rest, a bracket, means for 35 feeding the sheet over the support, and a member rigidly secured to the bracket and raised above the support in a position diagonally disposed to the direction of feed for wiping the strip across the secured-together 40 edges as the sheet is fed over the support.

3. A machine for wiping a strip across the edge of a sheet of material to one face of which, along the said edge, an edge of the strip is secured so that the strip and the sheet extend from the secured-together edges at an 45 angle to each other, the said machine having, in combination, a support upon which the sheet is adapted to rest, means for feeding the sheet over the support, and a rigidly secured member raised above the support in a position 50 diagonally disposed to the direction of feed for wiping the strip across the secured-together edges as the sheet is fed over the support.

55 4. A machine for folding a strip around the edge of a sheet of material to one face of which, along the said edge, an edge of the strip is secured so that the strip and the sheet extend from the secured-together edges at an 60 angle to each other, the said machine having, in combination, a support upon which the sheet is adapted to rest, means for feeding the sheet over the support, a rigidly secured member raised above the support for 65 wiping the strip across the secured-together

edges as the sheet is fed over the support, and a plow for folding the wiped portions of the strip around the secured-together edges.

5. A machine as described in Claim 4, in which the plow is spaced from the wiper in 70 the line of feed.

6. A machine for folding a strip around the edge of a sheet of material to one face of which, along the said edge, an edge of the strip is secured so that the strip and the sheet extend from the secured-together edges at an 75 angle to each other, said machine having, in combination, a support upon which the sheet is adapted to rest, means for feeding the sheet over the support, a rigidly secured member raised above the support for 80 wiping the strip across the secured-together edges as the sheet is fed over the support, and means for gagging the sheet and folding the wiped portions of the strip around the secured-together 85 edges.

7. A machine for folding a strip around the edge of a sheet of material to one face of which, along the said edge, an edge of the strip is secured so that the strip and the sheet extend from the secured-together edges at an angle to each other, the said machine having, in combination, a support upon which the sheet is adapted to rest, means for feeding the sheet over the support, a rigidly secured member raised above the support in a position 90 diagonally disposed to the direction of feed for wiping the strip across the secured-together edges as the sheet is fed over the support, and means for folding the wiped portions of the strip around the secured-together edges and pressing the folded portions of the strip into even contact with the other face of the sheet.

8. A machine for folding a strip around the edge of a sheet of material to one face of which, along the said edge, an edge of the strip is secured so that the strip and the sheet extend from the secured-together edges at an angle to each other, the said machine having, in combination, a support upon which the sheet is adapted to rest, means for feeding the sheet over the support, a rigidly secured member raised above the support in a position diagonally disposed to the direction of feed for wiping the strip across the secured-together edges as the sheet is fed over the support, means for gagging the sheet and folding the wiped portions of the strip around the secured-together edges, and means for 105 even contact with the other face of the sheet.

9. A machine for wiping a strip across the edge of a sheet of material to one face of which, along the said edge, an edge of the strip is secured so that the sheet and the strip extend from the secured-together edges at an angle to each other, the said machine having, in combination, means for feeding the sheet, and a wiper acting to wipe the strip across 110 115 120 125 130

the secured-together edges by dragging against the strip as the sheet is fed, the wiper being stationary during the operation of the machine.

5 10. A machine for folding a strip around the edge of a sheet of material to one face of which, along the said edge, an edge of the strip is secured so that the sheet and the strip extend from the secured-together edges 10 at an angle to each other, the said machine having, in combination, means for feeding the sheet, a wiper having a raised portion 15 diagonally disposed to the direction of feed acting to wipe the strip across the secured-together edges by dragging against the strip as the sheet is fed, and means for folding the wiped strip around the secured-together edges.

11. A machine for folding a strip around 20 the edge of a sheet of material to one face of which, along the said edge, an edge of the strip is secured so that the sheet and the strip extend from the secured-together edges at an angle to each other, the said machine 25 having, in combination, a wiper having a raised portion diagonally disposed to the direction of feed acting to wipe the strip across the secured-together edges by dragging against the strip as the sheet is fed, means for 30 folding the wiped portions of the strip around the secured-together edges, and means for feeding the sheet and pressing the folded portions of the strip into contact with the other face of the sheet.

35 12. A machine for folding a strip around the edge of a sheet of material to one face of which, along the said edge, an edge of the strip is secured so that the sheet and the strip extend from the secured-together edges at an angle to each other, the said machine having, in combination, a member for engaging the sheet and the strip at a point where the strip is secured to the sheet within the angle between the said one face of the sheet and the strip, the said member being 40 stationary during the operation of the machine, a member for engaging the margin near the said edge along the other face of the sheet at a point opposite to the point of action of the first-named member, means for applying pressure to one of the members to cause the said one member to exert a force toward the other member, and means for folding the strip around the secured-together edges.

45 55 13. A machine for folding a strip around the edge of a sheet of material to one face of which, along the said edge, an edge of the strip is secured so that the sheet and the strip extend from the secured-together edges at an angle to each other, the said machine having, in combination, a raised member for engaging the sheet and the strip at a point where the strip is secured to the sheet within the angle between the said one face of the sheet and the strip, the said member being

stationary during the operation of the machine, a member for pressing upon the other face of the sheet at a point opposite to the point of action of the first-named member, and means for folding the strip around the 70 secured-together edges.

5 14. A machine for folding a strip around the edge of a sheet of material to one face of which, along the said edge, an edge of the strip is secured so that the sheet and the strip 10 extend from the secured-together edges at an angle to each other, the said machine having, in combination, a support upon which the sheet is adapted to rest, means for feeding the sheet over the support, a rigidly secured 15 member raised above the support for engaging the sheet and the strip at a point where the strip is secured to the sheet within the angle between the said one face of the sheet and the strip, a member for pressing 20 upon the other face of the sheet at a point opposite to the point of action of the first-named member, and means for folding the strip around the secured-together edges.

25 15. A machine for folding a strip around the edge of a sheet of material to one face of which, along the said edge, an edge of the strip is secured so that the sheet and the strip extend from the secured-together edges at an angle to each other, the said machine having, 30 in combination, a support upon which the sheet is adapted to rest, means for feeding the sheet over the support, a rigidly secured member raised above the support for engaging the sheet and the strip at a point where the strip is secured to the sheet within the angle between the said one face of the sheet and the strip, a member for pressing upon the other face of the sheet at a point opposite to the point of action of the first-named member, and means for folding the strip around 35 the secured-together edges.

40 16. A machine for folding a strip around the edge of a sheet of material to one face of

which, along the said edge, an edge of the strip is secured so that the sheet and the strip extend from the secured-together edges at an angle to each other, the said machine having, in combination, a support upon which the sheet is adapted to rest, means for feeding the sheet over the support, a rigidly secured member raised above the support for engaging successive portions of the sheet and the strip at points where the strip is secured to the sheet within the angle between the said one face of the sheet and the strip, a member for pressing upon the other face of the sheet at points opposite to the points of action of the first-named member, and means for folding successive portions of the strip successively around the secured-together edges and pressing them into contact with the said other face of the sheet.

- the edge of a sheet of material to one face of which, along the said edge, an edge of the strip is secured so that the sheet and the strip extend from the secured-together edges at an angle to each other, the said machine having, in combination, a support upon which the sheet is adapted to rest and over which the sheet is adapted to be fed, a member raised above the support adapted to engage the sheet as the sheet is fed over the support, the member being stationary during the operation of the machine, means for folding the strip around the secured-together edges, and means independent of the member for pressing the strip into contact with the other face of the sheet. 5
18. A machine for folding a strip around the edge of a sheet of material to one face of which, along the said edge, an edge of the strip is secured so that the sheet and the strip extend from the secured-together edges at an angle to each other, the said machine having, in combination, a support upon which the sheet is adapted to rest and over which the sheet is adapted to be fed, a member raised above the support in a position diagonally disposed to the direction of feed adapted to engage the sheet as the sheet is fed over the support, the member being stationary during the operation of the machine, means for folding successive portions of the strip around the secured-together edges at a position in the line of feed forward of the member, and means for pressing the folded portions of the strip into even contact with the other face of the sheet. 20
19. A machine for folding a strip around the edge of a sheet of material to one face of which, along the said edge, an edge of the strip is secured so that the sheet and the strip extend from the secured-together edges at an angle to each other, the said machine having, in combination, means for moving portions of the unsecured edge of the strip across the secured-together edges, means for engaging the margin near the said edge along the other face of the sheet at a point opposite to the point of action of the moving means, and means for maintaining the moving means and the engaging means continuously pressed yieldingly towards each other. 40
20. A machine for folding a strip around the edge of a sheet of material to one face of which, along the said edge, an edge of the strip is secured so that the sheet and the strip extend from the secured-together edges at an angle to each other, the said machine having, in combination, a wiper for engaging the sheet and the strip at a point where the strip is secured to the sheet within the angle between the said one face of the sheet and the strip and for wiping the strip from the said point across the secured-together edges, a member for engaging the margin near the said edge along the other face of the sheet at a 55
- point opposite to the point of action of the wiper, means for maintaining the wiper and the engaging means continuously pressed yieldingly towards each other, and means for folding the strip around the secured-together edges and pressing it into contact with the said other face of the sheet. 70
21. A machine for folding a piece of work, having in combination, a support for the work, feeding, folding and folding-pressing members, and a binding-engaging wiper located beneath the work, the operative face of which lies at an angle to the line of feed. 75
22. The method of wiping out a binding strip which is attached at one edge by a line of stitches to the edge of a piece of sheet material which comprises engaging the free portion of the strip adjacent its line of attachment and intermittently wiping a free portion of the strip obliquely with respect to said line across said line. 80
23. A machine for operating upon a piece of work which consists of a piece of sheet material to one side of which a strip of binding is attached having, in combination, a support, means for feeding the work over the support with that side of the work to which the binding is attached resting upon the support, a wiper projecting above the support, extending at an angle to the line of feed and adapted when the work is fed over it to wipe a free portion of the binding over the attached portion thereof, and means for folding the remaining free portion of the binding about the edge of the material and for pressing it into place. 90
24. A machine for operating upon a piece of work which consists of a piece of sheet material to one side of which a strip of binding is attached having, in combination, a wiper held from movement in the line of feed and extending in a direction oblique to said line, means for feeding over the wiper that side of the work to which the binding is attached so as to cause the binding to be pulled out, and means for thereafter folding the binding over the edge of the material. 105
25. In a machine for operating upon a piece of work consisting of a piece of sheet material to which a strip of binding is attached the combination with means for feeding the work of a stationary wiper over which the work is fed, said wiper extending in a direction oblique to the line of feed so as to exert a drag upon the free portion of the binding in a direction to pull said free portion over the attached portion thereof. 110
26. A machine for operating upon a piece of work consisting of a piece of sheet material to which a strip of binding is attached having, in combination, a support for the work, means for feeding the work intermittently over the support, a member arranged at an angle to the line of feed and adapted to wipe a free portion of the binding strip ob- 125

- liquely across the attached portion, and means closely adjacent to the wiping member for folding the free portion of the strip over upon the body of the work as said portion leaves the wiping member.
5. 27. A machine for operating upon a piece of work, consisting of a piece of sheet material and a strip of fabric which are attached together near two edges of the respective articles having, in combination, a support for the work, means for feeding the work intermittently over the support, and a member for wiping the free portion of the strip over the attached portion in a direction oblique to the line of feed.
10. 28. A machine for operating upon a piece of work which comprises a piece of sheet material to an edge of which the edge of a binding strip is attached by a line of stitches having, in combination, means for supporting the work, and means for intermittently wiping successive parts of a free portion of the binding obliquely across the line of attachment.
15. 29. A machine for operating upon a piece of work which comprises a piece of sheet material to an edge of which the edge of a binding strip is attached by a line of stitches having, in combination, means for supporting the work, means for intermittently wiping successive parts of a free portion of the binding obliquely across the line of attachment, and means for folding the remaining free portion of the binding about the edge of the material and for pressing it down upon the margin of the material.
20. 30. A machine for operating upon a piece of work consisting of a piece of sheet material and a binding strip which are attached to each other near two edges of the respective articles, having in combination, a support for the work, means for feeding the work intermittently over the support, and a member held from movement in the line of feed adapted to engage the strip adjacent to its line of attachment and to act during the intermittent feed movements to wipe free portions of the strip obliquely with respect to said line across said line.
25. 31. A method of operating upon a piece of work consisting of a piece of sheet material and a binding strip which are attached to each other near two edges of the respective articles by a line of stitches, the said method comprising feeding the work, and engaging the work with a member immovable in a direction at an angle to the line of feed to move the strip tightly away from the line of stitches.
30. 32. A method of operating upon a piece of work consisting of a piece of sheet material and a binding strip which are attached to each other near two edges of the respective articles by a line of stitches, the said method comprising engaging the work with a member that is immovable in a direction at an angle to the line of stitches and relatively moving the work and the member to move the strip tightly away from the line of stitches.
33. A method of operating upon a piece of work consisting of a piece of sheet material and a binding a strip which are attached to each other near two edges of the respective articles by a line of stitches, the said method comprising engaging the work with a member that is immovable in a direction at an angle to the line of stitches, and relatively moving the work and the member in a direction such as to cause the member to move the strip tightly away from the line of stitches.
34. The method of folding a strip around the edge of a sheet of material to one face of which, along the said edge, an edge of the strip is stitched so that the sheet and the strip extend from the stitched-together edges at an angle to each other, the said method comprising feeding the work, engaging the work with a member that is immovable in a direction at an angle to the line of feed to move the strip tightly away from the stitches, and folding the strip around the secured-together edges and against the other face of the sheet.
35. The method of folding a strip around the edge of a sheet of material to one face of which, along the said edge, an edge of the strip is stitched so that the sheet and the strip extend from the stitched-together edges at an angle to each other, said method comprising feeding the work, engaging successive portions of the work with a member that is immovable in a direction at an angle to the line of feed to move the successive portions of the strip tightly away from the stitches, and folding the successive portions of the strip around the secured-together edges and against the other face of the sheet.
36. The method of folding a strip around the edge of a sheet of material to one face of which, along the said edge, an edge of the strip is stitched so that the sheet and the strip extend from the stitched-together edges at an angle to each other, said method comprising engaging the work with a member to move the strip tightly away from the stitches, engaging the margin near the said edge along the other face of the sheet at a point opposite to the point of action of the member to cooperate with the member in moving the strip tightly away from the stitches, maintaining the member and the engaging means yieldingly pressed towards each other, and folding the strip around the secured-together edges and against the other face of the sheet.
37. A machine for operating upon a piece of work consisting of a piece of sheet material and a binding strip which are attached to each other near two edges of the respective articles by a line of stitches, the said machine having, in combination, a support upon which the work is adapted to be supported

and over which the work is adapted to be fed, and a member immovable in a direction at an angle to the line of feed for engaging the work to move the strip tightly away from the line of stitches.

38. A machine for operating upon a piece of work consisting of a piece of sheet material and a binding strip which are attached to each other near two edges of the respective articles by a line of stitches, the said machine having, in combination, a support upon which the work is adapted to be supported, a member immovable in a direction at an angle to the line of stitches for engaging the work, and means for relatively moving the work and the member to move the strip tightly away from the line of stitches.

39. A machine for operating upon a piece of work consisting of a piece of sheet material and a binding strip which are attached to each other near two edges of the respective articles by a line of stitches, the said machine having, in combination, a support upon which the work is adapted to be supported, a member immovable in a direction at an angle to the line of stitches for engaging the work, and means for relatively moving the work and the member in a direction such as to cause the member to move the strip tightly away from the line of stitches.

40. A machine for folding a strip around the edge of a sheet of material to one face of which, along the said edge, an edge of the strip is stitched so that the sheet and the strip extend from the secured-together edges at an angle to each other, the said machine having, in combination, means for feeding the work and folding the strip around the secured-together edges and against the other face of the sheet, and means immovable in a direction at an angle to the line of feed for engaging the work to move the strip tightly away from the stitches.

41. A machine for folding a strip around the edge of a sheet of material to one face of which, along the said edge, an edge of the strip is stitched so that the sheet and the strip extend from the secured-together edges at an angle to each other, the said machine having, in combination, means for feeding the work and folding successive portions of the strip around the secured-together edges and against the other face of the sheet, and means immovable in a direction at an angle to the line of feed for engaging successive portions of the work to move the said successive portions of the strip tightly away from the stitches.

42. A machine for folding a strip around the edge of a sheet of material to one face of which, along the said edge, an edge of the strip is stitched so that the sheet and the strip extend from the secured-together edges at an angle to each other, the said machine having, in combination, a member for engag-

ing the work to move the strip tightly away from the stitches, means for engaging the margin near the said edge along the other face of the sheet at a point opposite to the point of action of the member to cooperate with the member in moving the strip tightly away from the stitches, means for maintaining the member and the engaging means continuously pressed yieldingly towards each other, and means for folding the strip around the stitched-together edges and against the other face of the sheet.

43. A machine for folding a strip around the edge of a sheet of material to one face of which, along the said edge, an edge of the strip is secured so that the sheet and the strip extend from the secured-together edges at an angle to each other, said machine having, in combination, means for feeding the sheet, a wiper for wiping the strip across the secured-together edges as the sheet is fed, and a plow for folding the wiped portions of the strip around the secured-together edges.

44. A machine for folding a strip around the edge of a sheet of material to one face of which, along the said edge, an edge of the strip is secured so that the sheet and the strip extend from the secured-together edges at an angle to each other, said machine having, in combination, means for feeding the sheet, a wiper for wiping the strip across the secured-together edges as the sheet is fed, a plow for initially folding the wiped portions of the strip around the secured-together edges, and means for pressing the folded portions of the strip against the other face of the sheet.

45. A machine for folding a strip across the edge of a sheet of material to one face of which, along the said edge, an edge of the strip is secured so that the sheet and the strip extend from the secured-together edges at an angle to each other, said machine having, in combination, means for feeding the sheet, and a wiper acting to wipe the strip across the secured-together edges by dragging against the strip as the sheet is fed.

46. A machine for operating upon a piece of work consisting of a piece of sheet material and a binding strip which are attached to each other near two edges of the respective articles by a line of stitches, the said machine having, in combination, a member immovable in a direction at an angle to the line of feed for engaging one face of the sheet and the strip at the stitch line to move the strip tightly away from the stitch line, and a retainer for pressing against the other face of the sheet at a point opposite to the point of action of the member.

47. The method of folding a strip around the edge of a sheet of material to one face of which, along said edge, an edge of the strip is stitched so that the sheet and the strip extend from the secured-together edges at an angle to each other, said method comprising

ing engaging the said face of the sheet and the strip at the stitch line with a member that is immovable in a direction at an angle to the line of feed and continuously pressing against 5 the other face of the sheet at a point opposite to the point of action of the member to move the strip tightly away from the stitch line, initially folding the moved strip around the stitched-together edges and finally folding 10 and pressing the initially folded strip against the other face of the sheet.

48. A machine for folding a strip around the edge of a sheet of material to one face of which, along said edge, an edge of the strip 15 is stitched so that the sheet and the strip extend from the stitched-together edges at an angle to each other, said machine having, in combination, a member immovable in a direction at an angle to the line of feed for engaging the said face of the sheet and the strip at the stitch line to move the strip tightly away from the stitch line, a retainer for pressing 20 against the other face of the sheet at a point opposite to the point of action of the member, means for initially folding the strip around the stitched-together 25 edges and finally folding and pressing the initially-folded strip against the other face of the sheet.

edges, and means for finally folding and pressing the initially folded strip against the other face of the sheet.

49. A machine for folding a strip around 30 the edge of a sheet of material to one face of which, along said edge, an edge of the strip is stitched so that the sheet and the strip extend from the stitched-together edges at an angle to each other, said machine having, in 35 combination, a member immovable in a direction at an angle to the line of feed for engaging the said face of the sheet and the strip at the stitch line to move the strip tightly away from the stitch line, a retainer 40 for continuously pressing against the other face of the sheet at a point opposite to the point of action of the member, a plow for initially folding the moved strip around the stitched-together edges, and means for finally folding 45 and pressing the initially-folded strip against the other face of the sheet.

In testimony whereof, I have hereunto subscribed my name this 10th day of August, 1922.

ANDREW R. RIDDERSTROM.
